FIG. 1.

FIG. 2.

FIG. 3.

FIG. 4.

INVENTOR.
F. Giudice,

BY
Geo. P. Kammel.
ATTORNEY.

UNITED STATES PATENT OFFICE.

FRANK GIUDICE, OF NEW YORK, N. Y.

LIFE PRESERVER.

Application filed February 27, 1924. Serial No. 695,506.

To all whom it may concern:

Be it known that I, FRANK GIUDICE, a subject of the King of Italy, residing at New York city, in the county of New York and State of New York, have invented certain new and useful Improvements in Life Preservers, of which the following is a specification.

This invention relates to a life preserver, and has for its object to provide a device of such class, in a manner as hereinafter set forth, for supporting the wearer upright in water even though the wearer be unconscious, and further whereby a greater lifting power will be obtained thereby than that present in the types of life preservers now in general use.

A further object of the invention is to provide, in a manner as hereinafter set forth, a life preserver including a protecting element adapted to be secured to the front of the body of the wearer for protection from jars and bumps, and further to provide the device with a pair of inflatable buoyant elements flexibly connected with the protecting element and constituting sustaining or lifting means for holding the wearer high in the water when the device is in use.

A further object of the invention is to provide, in a manner as hereinafter set forth, a life preserver including a body protecting element and a pair of sustaining or lifting elements connected to the protecting element and capable of being shifted to the desired position where lifting is needed, and further capable of being shifted by the wearer from front and rear to prevent them from hampering the wearer when the device is in use.

Further objects of the invention are to provide in a manner as hereinafter set forth, a life preserver, which is simple in its construction and arrangement, readily secured to and removed from the wearer, strong, durable, compact, thoroughly efficient in its use, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood

that changes, variations and modifications can be resorted to which come within the scope of the claims hereunto appended.

In the drawings wherein like reference characters denote corresponding parts throughout the several views:

Figure 1 is a rear elevation of a life preserver, in accordance with this invention and with the elements thereof extended.

Figure 2 is a side elevation of a life preserver when folded.

Figure 3 is a section on line 3-3, Figure 1.

Figure 4 is a section on line 4-4, Figure 1.

A life preserver, in accordance with this invention, comprises a body protecting element, a pair of inflatable buoyant elements constituting lifting or sustaining means and flexibly connected with the body protecting element, and securing means for the body protecting element.

The body protecting element consists of a strip of wood 1, of the desired shape or of the desired length, width and thickness, and as illustrated by way of example the strip 1 is of oval contour but it is to be understood that it can be of any shape desired. The front and rear of the strip 1 have secured thereto a series of spaced transversely extending metallic straps 2. In Figure 1 of the drawings, the back of the strip 1 is shown as provided with the straps 2, but it is to be understood that the front of the strip 1 has a like arrangement of the straps 2. In Figure 3 of the drawings, one of the straps 2 is shown upon the front of the strip 1. The straps 2 are provided for reinforcing purposes and prevent the wood from cracking. The straps are constructed of thin metallic material but of the necessary strength to obtain the desired rigidity. The edge of the strip 1 is protected and reinforced throughout through the medium of a split metallic band 3, channel shaped in cross section, whereby the band 3 will overlap the front and back of the strip 1, as shown in Figure 3.

Secured to the top of the band 3, at each upper corner of the body protecting element, is an eye 4, and to each of the latter is secured, as at 15, the end of a neck band 6.

Secured to one side of the band 3, at the back thereof, is a pair of flexible straps 7,

of substantial length and provided with openings 8. Secured to the other side of the band 3, at the back thereof, is a pair of flexible straps 9, each provided with a buckle 10. The straps 9 are of less length than the straps 7, and the latter are fixedly secured to the band 3, by the hold-fast devices 11. The straps 9 are secured to the band 3 by the hold-fast devices 12. The straps 7 and 9 provide means for securing the protecting element to the front of the body of the wearer and when said element is in such position it protects the wearer from jars and bumps. The openings 8 in the straps 7, in connection with the buckles 10, provide an adjustable securing means for the protecting element.

When the protecting element is connected to the wearer, the neck band 6 is inserted over the head of the wearer and after the protecting element has been connected to the wearer by the neck band 6, it is fixedly secured in position by the straps 7 and 9.

A pair of inflatable buoyant elements is employed and said elements constitute sustaining or lifting means, and as each of said elements is of the same construction, but one will be described as the description of one will apply to the other. Each of said elements consists of a flexible outer casing 13, somewhat elliptical in contour and preferably constructed of canvas, but it is to be understood that the material from which the casing 13 is set up can be other than canvas, and arranged within the casing 13 is an inflatable resilient inner casing 14, provided with a valved air inlet tube 15 of known construction which extends through and projects from the casing 13. The valved air inlet tube 15 is arranged at the inner side of the element near the top thereof and carries a removable closure cap 16. The inflatable buoyant elements are oppositely disposed with respect to each other and each arranged at one side of the protecting element.

The inflatable buoyant elements are generally referred to by the reference characters 17 and 18 and the outer casing of each of said elements has throughout opposed marginal portions 19 and 20, between which extend throughout opposed marginal portions 21, 22 of the casing 14.

The element 17 is connected to one side of the protecting element by a pair of flexible members 23, in the form of short length chains, but it is obvious that the members 23 can be set up of any suitable material.

The element 18 is connected to the other side of the protecting element by a pair of flexible members 24, as shown short length chains, but it is obvious that the members 24 can be constructed of any suitable material.

The elements 17 and 18 when inflated, provide means for holding the wearer high in

the water when the device is used and furthermore the elements can be shifted to the desired position with respect to the wearer, to the point where lift is needed, and furthermore the buoyant elements can be shifted from front and rear so as not to hamper the wearer. The buoyant elements are of suitable size so as to obtain great lifting power and further when inflated will support the wearer in upright position even though the wearer be unconscious.

When the device is not used it can be folded in a compact manner as shown in Figure 2.

It is thought that the many advantages of a life preserver as hereinbefore referred to, can be fully understood, particularly in view of the fact that the device is so set up that it will not only sustain the wearer or lift the wearer but will furthermore act as a protecting means for the body of the wearer, and although the preferred embodiment of the invention is as illustrated and described, yet it is to be understood that changes in the details of construction can be had which will fall within the scope of the invention as claimed.

What I claim is:—

1. A life preserver comprising a protecting element for the body of the wearer and including a strip of wood, transversely extending metallic reinforcing straps secured to both faces of said strip, a metallic reinforcing band inclosing the edges of said strip throughout, a pair of inflatable sustaining elements, chains connecting said sustaining elements to the sides of said band, and means connected to said band for securing the protecting element to the body of the wearer.

2. A life preserver comprising a protecting element for the body of the wearer and including a strip of wood, transversely extending metallic reinforcing straps secured to both faces of said strip, a metallic reinforcing band inclosing the edges of said strip throughout, a pair of inflatable sustaining elements, chains connecting said sustaining elements to the sides of said band, means connected to said band for securing the protecting element to the body of the wearer, and a neck band secured to the upper end of said band.

3. A life preserver comprising a wooden protecting element for the body of the wearer and provided with metallic reinforcing and protecting means, an inflatable sustaining element arranged at each side of the protecting element, a pair of flexible members for connecting each inflatable element to the protecting element, and means carried by the protecting element for detachably securing it to the body of the wearer.

4. A life preserver comprising a wooden protecting element for the body of the wear-

er and provided with metallic reinforcing and protecting means, an inflatable sustaining element arranged at each side of the protecting element, a pair of flexible members for connecting each inflatable element to the protecting element, means carried by the protecting element for detachably securing

it to the body of the wearer, and a neck band secured to the upper end of the protecting element.

10 In testimony whereof, I affix my signature hereto.

FRANK GIUDICE.
